MACHINE FOR CHARGING ANNEALING
FURNACES AND THE LIKEHomer Buck and Harvey W. Ball, Alliance, Ohio,
assignors to The Morgan Engineering Company,
Alliance, Ohio

Application March 4, 1935, Serial No. 9,310

6 Claims. (Cl. 214—26)

This invention relates to improvements in machines for charging annealing furnaces and the like and more particularly to improvements in the charging machine disclosed in the application of Harvey W. Ball, Serial No. 6357, filed February 13, 1935.

In the machine disclosed in said application, a pair of trucks are employed and they are adapted to be moved into and out of a furnace. 10 Each truck includes an elongated wheel-supported body provided with elevating platforms, and motor-driven means comprising worm gearing is employed for raising and lowering the platforms. The primary purpose of the present invention is to provide novel means for raising and lowering the platforms from a prime mover which means is believed to be superior to the one disclosed in said application.

The general arrangement of the new charging machine and its functioning is the same as the one shown and described in said application, the only difference being that the mechanism for raising and lowering the load is of a different design and one which we believe will prove cheaper to produce and perhaps more practical in operation than the one disclosed in said application.

With the foregoing object outlined and with other objects in view which will appear as the 30 description proceeds, the invention consists in the novel features hereinafter described in detail, illustrated in the accompanying drawings, and more particularly pointed out in the appended claims.

35 In the drawings:

Fig. 1 is a plan view of one of the improved trucks of the new machine.

Fig. 2 is a side elevation of the same.

40 Fig. 3 is a vertical longitudinal section of a portion of one of the new trucks, taken on the line 3—3 of Fig. 1.

Fig. 4 is a transverse vertical sectional view of the new truck taken on the line 4—4 of Fig. 2.

45 Fig. 5 is a vertical sectional view of a detail taken on the line 5—5 of Fig. 3.

To facilitate illustration we have shown only one of the trucks, but as disclosed in said application, two of these trucks are used in the actual machine and they are moved simultaneously in 50 and out of a charging furnace not shown.

Referring to the drawings, 1 designates an elongated truck body carried by wheels 2 which roll on tracks not shown. A horizontal rack 3 depends from the body and engages a pinion 4 having a fixed axis, and designed to move the

truck into and out of the furnace. The truck is constructed to support annealing pans or boxes 7 carried by elevating platforms 8. Each truck is preferably provided with a plurality of such platforms and they move vertically in wells or guide ways 8a.

For the purpose of operating the platforms, the truck has a prime mover 9 equipped with suitable reduction gearing not illustrated, and driving a screw 10. This screw is in threaded engagement with a nut 11 that is moved back and forth longitudinally of the truck by the screw, and the nut operates links 12 which connect the nut to a horizontal rack 13. The rack 13 has gear teeth 13a arranged at suitable places along the underside of the rack for the purpose of operating pinions 14 mounted on rotatable cross shafts 16 carried by suitable bearings 16a positioned at opposite sides of the truck. Each pinion 14 has oppositely disposed eccentric hubs 14a which engage anti-friction bearings 15 arranged in rings 15a upon which the platforms 8 rest. Obviously when the rack 13 is moved in the proper direction the pinions 14 will turn and their hubs 14a will cooperate with the rings 15a to lift the platforms.

Horizontal rollers 19, as best shown in Fig. 5, extend transversely of the truck body and are mounted in anti-friction bearings 19a. The central portion 19b of these rollers bear upon the rack 13 to keep it in engagement with the pinions 14, and the end portions of these rollers extend through vertical slots 19c.

In operation it will be understood that when the movement of the nut 11 causes the gears 14 to rotate, a vertical movement is imparted to the lifting tables 8 which directly bear upon the rings 15a which house the bearings 15. When the pans 7 or the like are lifted in this manner they may be carried into a furnace in a raised position and lowered on to the furnace piers. The lifting tables being lowered further by continuing the same movement will clear the pans 7 and the charger can then be racked out of the furnace on to the transfer car, not shown. The lifting tables are then at a suitable elevation to pass under other annealing pans on the storage platforms and by operating the mechanism, described above, the lifting tables will be raised again to the necessary height for carrying them into the furnace.

From the foregoing it is believed that the construction, operation and advantages and the invention may be readily understood by those skilled in the art and we are aware that changes

may be made in the details disclosed without departing from the spirit of the invention as expressed in the claims.

What is claimed and desired to be secured by 5 Letters Patent is:

1. A charging machine for furnaces comprising a wheel-supported truck, an elevating platform carried by the truck, a gear mounted in the truck for rotation about a horizontal axis extending transversely of the truck, eccentric means movable with the gear for raising and lowering said platform, a longitudinally movable rack meshing with the gear for operating the latter, and means for limiting the upward movement 10 of the rack away from said gear.
2. A charging machine for furnaces comprising a wheel-supported truck, a lifting platform carried by the truck, a rotatable gear mounted in the truck for movement about a horizontal axis extending transversely of the truck, eccentric means movable with the gear for raising and lowering the platform, a longitudinally movable rack for actuating the gear, and rolling means for limiting the upward movement of the 15 rack away from the gear.
3. A charging machine for furnaces comprising a wheel-supported truck adapted to be moved into and out of a furnace, an elevating platform carried by the truck, horizontal cross shafts 20 mounted in the truck, gears mounted on said shafts, each gear having oppositely extending eccentric hubs operatively engaging the platform for operating the latter, a rack engageable with the gears, means for maintaining said rack in engagement with said gears, and means for moving the rack longitudinally.
4. A charging machine for furnaces comprising a wheel-supported truck adapted to be moved into and out of a furnace, an elevating platform carried by the truck, horizontal cross 25

shafts mounted in the truck, gears mounted on said shafts, each gear having oppositely extending eccentric hubs operatively engaging the platform for operating the latter, a rack engageable with the gears, means for actuating the rack, and rollers passing through the platform and bearing upon the rack for limiting the upward movement of the rack.

5. In a machine of the character described, a wheel-supported truck, an elevating platform 10 mounted on the truck, horizontal cross shafts supported by the truck, gears mounted on the cross shafts, each gearing having oppositely disposed eccentric hubs on which the platform rests, a rack engaging said gears for actuating 15 the same, a prime mover carried by the truck, means for actuating the rack from said prime mover, said platform being provided with slots, and rollers journaled in bearings on the truck, passing through said slots and engaging said 20 rack for limiting upward movement of the rack.

6. A charging machine for furnaces comprising a truck having a hollow elongated wheel supported body provided with a vertical guideway extending lengthwise of the body and opening through the top thereof, a vertically movable lifting platform guided by said guideway and adapted to be raised to a position above the body, horizontal cross shafts mounted within the body, gears mounted on said shafts, each gear 25 having oppositely extending eccentric hubs operatively engaging the platform for raising the latter, a motor housed within the body, and transmission means arranged within the body and operatively connecting the motor to said 30 gears for raising the platform by the operation of the motor.

HOMER BUCK,
HARVEY W. BALL.
